BORDERED RUG OR SIMILAR ARTICLE

Andrew E. Lawrence, San Mateo, Calif., assignor to Fabco Products Inc., San Francisco, Calif., a corporation of Delaware

Application October 13, 1951, Serial No. 16,931

Term of patent 7 years

(Cl. D92—21)

To all whom it may concern:

Be it known that I, Andrew E. Lawrence, a citizen of the United States, residing in the city of San Mateo, county of San Mateo, State of California, have invented a new, original, and ornamental Design for a Bordered Rug or Similar Article, of which the following is a specification, reference being had to the accompanying drawing, forming part thereof.

The drawing is a face view of a quarter-section of a bordered rug embodying my new design, which design is repeated symmetrically on each of the other three quarters of the rug.

I claim:

The ornamental design for a bordered rug or similar article, substantially as shown and described.

ANDREW E. LAWRENCE.
